FIG. 1

The characteristic features of my design for a baseball home plate reside in the combination of a baseball home plate having dark elongated strips inwardly extending from the apex of the shorter sides as shown.

I claim:

The ornamental design for a baseball home plate, as shown and described.
